UNITED STATES PATENT OFFICE.

JAMES O. NASH, OF DUKE, OKLAHOMA.

PUMP.

Application filed March 30, 1926. Serial No. 98,541.

This invention relates to pumps and has for its object the provision of a strong and durable mechanism whereby the strain upon the motor in operating a pump will be materially diminished and so equalized and distributed that the only work required of the motor will be to lift the weight of the water. The invention is illustrated in the accompanying drawings and will be hereinafter 10 first fully described and then more particularly pointed out in the appended claims.

In the drawings:

Figure 1 is an elevation, with parts broken away and in section, of one embodiment of the invention;

Fig. 2 is a top plan view of the same;

Fig. 3 is a horizontal section on the line 3—3 of Fig. 1;

Fig. 4 is a view similar to Fig. 1 but 20 showing another embodiment of the invention;

Fig. 5 is a detail perspective view showing the form of a counterweight and the means for carrying the same;

Fig. 6 is a view in perspective showing 25 the means for connecting the pump rod with the operating lever, the parts being disassembled but approximately in their proper relation.

In the drawings, the reference numeral 1 indicates a platform or well curb or other fixed base or foundation. Secured upon this base are brackets 2 which are also secured to posts 3 which are preferably constructed of wood of suitable dimensions and reinforced by metal facing strips 4, the use of the wood providing the necessary strength without excessive cost and the metallic facing strips preventing warping or twisting 40 of the wooden bodies. These posts are set up at the proper distances apart and preferably in rectangular relation, and to their upper ends are secured cross bars 5 whereby rigidity is imparted to the structure and the posts maintained in the proper spaced relation, similar cross bars or beams 7 being secured to the posts below the top bars 5 and on the same sides thereof as will be understood. Also secured to the upper 50 ends of the posts and to the cross bars 5 are filler boards or blocks 8 which have their ends recessed or notched, as shown clearly in Fig. 2, whereby to fit around the posts. The inner longitudinal edges of

these filler blocks or beams 8 are spaced 55 apart so as to provide a slot or guideway 9 for the pump rod 10, and facing strips 11 of metal are preferably secured to the inner opposed faces of the blocks 8, as shown clearly in Fig. 2, to reduce the wear incident 60 to possible contact of the pump rod with the filler blocks. Spacers 12 are fitted between the ends of the wear strips 11, and the posts, cross bars 5, wear strips 11, filler blocks 8 and spacers 12 are all secured together by 65 the same bolts 13. To further guide the pump rod 10 and minimize the wear upon and by the same, rollers 14 are suitably mounted between and carried by the wear strips 11 and spaced apart such a distance 70 that, while they will guide the pump rod, they will not bear thereon with such force as to interfere with its free operation.

Between the cross bars 7, filler blocks 15, corresponding in all substantial respects to the blocks 8, are secured. A spacer 16 is provided between the blocks 15 at one side of the frame but at the opposite side these blocks 15 are cut out to define recesses 17 which accommodate the operating lever or 75 the link between a pair of operating levers in the operation of the pump. The combined width of the recesses 17 is substantially equal to the distance between the posts 3, as clearly shown in Fig. 3, and adjacent the 80 said recesses the opposed edges of the blocks 15 are suitably shaped to fit closely around a pump casing 18 and receive wear strips 19 immediately adjacent and at one side of the pump casing, the said wear strips carrying 85 between them rollers 20 of proper diameter to fit readily within the available space and bear against the opposite sides of a second pump rod 21.

In the form of the invention illustrated 95 in Figs. 1 to 3, the mechanism is adapted for operating two reciprocating pumps, one of the pumps drawing water upon the down-stroke of the main driving rod 10 and the other of said pumps drawing water on the 100 up-stroke of the same. The main operating rod 10 is connected directly with the plunger rod 22 working in the pump 18 and, near the lower end of the said main operating bar 10, links 23 are pivotally attached to opposite sides thereof. These links 23 are formed at their lower ends with outturned 105 terminals 24 which are circular in cross sec-

- tion whereby they constitute trunnions or pivots to be engaged in openings 25 provided therefor in the ends of straps 26 which are secured to opposite sides of a lever 27 which 5 is fulcrumed, as shown at 28, between the adjacent posts 3, bearing blocks 29 being preferably provided so that the lever will be held against lateral movement but permitted to oscillate freely in a vertical plane.
- 10 The straps 26 project beyond the outer end of the lever and their projecting ends are adapted to fit within grooves 30 in the sides of a counterweight 31, the counterweight, when used, being secured to the straps by 15 a bolt or other element 32 inserted through the ends of the straps and the body of the weight as will be understood. The described construction provides a very strong apparatus and the parts may be very easily and 20 cheaply procured and assembled. The pump rod 21 is secured to or formed with the plunger rod 33 working in the pump case 34, and to the said rod 21, near the lower end thereof, are pivotally secured links 35, 25 which correspond in all particulars to the links 23 previously described. The links 35 are pivotally engaged in straps 36 secured to the opposite sides of a wooden lever body 37 and project outwardly beyond the outer 30 ends of the said body to engage against the opposite sides of a handle member 38. The lever body 37 is pivotally supported, as at 39, by and between bearing blocks 40 secured to the inner opposed sides of the 35 adjacent posts 3, and a connecting bar or link 41 is provided to connect the inner end portion of the lever 36, 37 with the outer end portion of the lever 26, 27. This connecting bar 41 comprises a central wooden 40 body having its ends tapered, as shown at 42, whereby it will accommodate the relative angular positions of the two levers without interfering with the operation of the same, and metallic straps 43 secured to 45 the opposite sides of the said wooden body and projecting beyond the ends of the same to be pivotally attached to the respective levers, the levers being disposed between the ends of the straps 43, as will be understood.
- 50 The handle member 38 also comprises a wooden body having reinforcing metallic straps or plates 44 secured to its upper and lower sides and projecting beyond its end to fit over the upper and lower sides of the 55 bar or lever body 37, a bolt 45 being inserted through the ends of the body 37 and the straps 44 to secure the parts together. It will thus be seen that relative movement between the handle and the lever will be 60 prevented but the handle member may be easily removed when its use is not desired so that space may be saved in crating the parts for transportation or for storage.
- It is to be understood that the handle 65 member 38 is provided in order that the pump may be manually operated when desired, but it is intended that the pumps be operated by a power motor, as a wind wheel having its pitman or driving rod connected to the main driving or pump rod 10. The 70 pump may be driven by a steam or other engine, the pump jack for operating with the engine being connected to the lever 37 by a pivot bolt inserted through the opening 451 and the handle 38 being preferably 75 removed. The pivot 39 is located equidistant from the opening 451 and the trunnions of the links 35, thus giving an engine the same power and practically the same 80 stroke that it would have if connected directly to the pump rod 10 or 21, as is now generally done. When the invention is applied to two pumps, as shown in Fig. 1, the plungers and pump rods of the two pumps will counterbalance each other so that the 85 strain upon the wind wheel in this respect will be equalized and so distributed that the wind wheel will be called upon merely to overcome the weight of the portion of water which is to be raised. The two levers and 90 the intermediate connecting bar serve to transmit the motion of the main driving rod from the main pump to the second pump so that the two plungers will move in opposite directions at all times. In this embodiment of the invention, the counterweight is unnecessary.
- In Fig. 4, I have illustrated the invention applied to a single pump 46. The supporting frame, indicated by the numeral 47, 95 corresponds in all respects to the supporting frame previously described and shown in Figs. 1, 2 and 3. The main driving rod 48 is formed with or connected directly to the plunger rod 49 of the pump and carries links 100 50 which are identical with the links 23 and 35. A lever 51, which corresponds with the lever 26, 27 first described, is fulcrumed at 52 upon the supporting structure and has its inner end pivotally engaged with the links 105 50, while its outer end carries the counterweight 30. Below the lever 51, a lever 54 is pivotally mounted upon the supporting structure, and this lever 54 may be the working portion of the lever 36, 37, but the fulcrum 55 is disposed nearer the inner edges of the posts 3 than is the fulcrum 39, as will be noted upon comparison of Fig. 1 with Fig. 4 of the drawings. The connecting bar 110 56 is like the connecting bar 41 in construction and is pivoted at its upper end to the lever 51 near the outer end thereof and at its lower end to the lever member 54. In this form of the invention, the counterweight should balance the weight of all the 115 parts of the operating mechanism, and it will, of course, be noted that the lever 54 is merely provided to facilitate the attachment of a handle member corresponding to the handle member 38 when it is desired to 120 125 130

operate the pump manually, the levers 51 and 54 moving in the same direction at all times instead of in opposite directions as do the levers in the first described form. In 5 this arrangement, the pivots 52 and 55 are in the same vertical plane and the distance between the pivot 52 and the pivot 53 is the same as the distance between the pivot 53 and the pivot 57, the levers 51 and 54 being 10 parallel at all times so that the exact stroke of the driving agent will be imparted to the pump rod. To drive this form of the invention by an engine, the pump jack of the engine is connected to the lever 54 and the bar 15 56 by the pivot bolt 57. If a very tall jack be employed, it may be connected to the lever 51 at the pivot 53, although the distance to such connection is greater than is usually deemed desirable. When operating with a 20 wind wheel, the pitman of the wind wheel is connected directly to the driving rod 48, and the lever 54 and connecting bar 56 may be omitted. The counterweight, when operating by a wind wheel, may be slightly 25 less than the weight of the plunger and the pump rod so that the wind wheel will not be required to force the latter on the down stroke.

It will be readily noted from the foregoing description, taken in connection with the accompanying drawings, that I have provided a very simple and compact pumping mechanism whereby the strain will be minimized so that the driving force will be more 30 effectually utilized than heretofore and the water drawn from a deep well more rapidly and easily than has heretofore been done. In the first described form of the invention, water may be delivered at the mouth of the 35 well in a continuous stream with no greater expenditure of force than has heretofore been necessary to deliver an intermittent stream from a single pump.

Having thus described the invention, I 40 claim:

1. In a pumping mechanism, the combination of a plurality of posts, metallic facing strips secured along the said posts, cross bars connecting the posts at their upper ends and 45 at points below their upper ends, filler blocks secured to the inner opposed faces of said cross bars and the posts and having their inner longitudinal edges spaced apart to define guiding slots, a pump rod mounted to 50 reciprocate through the said guiding slots, and a lever fulcrumed upon the posts at one

side of the pump rod and connected at its inner end with the pump rod.

2. In a pumping mechanism, the combination of posts, cross bars connecting the posts, 55 filler blocks secured to the cross bars and the posts and fitting between the posts, wear strips provided on the inner opposed longitudinal edges of the filler blocks, guiding elements carried by said strips, a pump rod 60 working in the space between the wear strips and engaging between said guiding elements, and a lever fulcrumed upon the posts between the upper and lower cross bars and having its inner end operatively connected with the 65 pump rod.

3. In a pumping mechanism, the combination of a supporting structure, a pump rod mounted for reciprocation therein, a lever fulcrumed between its ends directly upon the 70 supporting structure and having its inner end operatively connected with the pump rod, a second lever fulcrumed directly upon the supporting structure below the first-mentioned lever, and a connecting bar extending 75 between and pivoted to the two levers.

4. In a pumping mechanism, the combination of a supporting structure, a pump rod mounted in the supporting structure for vertical reciprocation, a lever fulcrumed upon 80 the supporting structure at one side of the pump rod, and links pivoted at their upper ends to the opposite sides of the pump rod and provided at their lower ends with out-turned trunnions pivotally engaged in the 85 end of the lever.

5. In a pumping mechanism, the combination of a supporting structure, a pair of pumps disposed within the supporting structure, pump rods working in the respective 90 pumps and guided by the supporting structure, a lever fulcrumed between its ends directly upon the supporting structure in the upper portion of the same, links connecting the inner end of said lever with one pump 95 rod, a second lever fulcrumed directly upon the supporting structure below the first-mentioned lever, links connecting the inner end of the second-mentioned lever with the second pump rod, and a connecting bar extending 100 between the levers and having its upper end pivoted to the upper lever at the outer side of the fulcrum thereof and its lower end pivoted to the lower lever at the inner side of the fulcrum of the same. 105

In testimony whereof I affix my signature.
JAMES O. NASH. [L.S.]
